(57) **CLAIM**

The ornamental design for a portion of urinal, as shown and described.

DESCRIPTION

FIG. 1 is a perspective view of a portion of urinal, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a sectional view thereof.

The broken line showing of the portion of urinal is for the purpose of illustrating article and forms no part of the claimed design.
